UNITED STATES PATENT OFFICE.

HENRY Z. COBB, OF WINCHESTER, MASSACHUSETTS, ASSIGNOR TO REVERE RUBBER COMPANY, A CORPORATION OF RHODE ISLAND.

METHOD OF MAKING RESILIENT BALLS AND APPARATUS THEREFOR.

1,270,008.

Specification of Letters Patent. Patented June 18, 1918.

Application filed January 10, 1917. Serial No. 141,557.

To all whom it may concern:

Be it known that I, HENRY Z. COBB, a citizen of the United States, residing at Winchester, county of Middlesex, and State of Massachusetts, have invented certain new and useful Improvements in Methods of Making Resilient Balls and Apparatus Therefor, of which the following is a full, clear, and exact description.

My invention relates to improvements in resilient balls and particularly balls for playing various games, such as golf and similar games. The object of my invention is the production of a ball which has the highest resiliency, combined with greatest balance, symmetry and durability. The ball, of which the method of making and apparatus therefor form the subject matter of this application, is particularly described and claimed in my co-pending application filed December 14, 1916, Serial No. 136,869.

For a detailed description of one embodiment of my invention, reference may be had to the following specification and to the accompanying drawing forming a part thereof, in which:

Figure 1 is a transverse sectional view of my improved ball;

Fig. 2 is an elevation of the soft elastic center of the ball which is preferably provided with a metallic core;

Fig. 3 is a transverse sectional view of the mold for forming the latter; and

Fig. 4 is a plan view of the equatorial ring portions of the mold segregated from the main portions thereof.

Briefly stated, the ball when intended for use in playing golf consists preferably of a central metallic core 1, such as an accurately ground steel ball of the proper size to give the required weight to the ball. About the central core 1 is molded a body of elastic, resilient material 2 of any suitable composition, preferably vulcanizable rubber. This elastic composition is provided with a plurality of tapering holes or pockets 3 which extend into or through the composition to the central metallic core 1. The central layer of elastic composition is then preferably covered with a thin skin or jacket 4 of rubber in the form of a small bag of substantially pure rubber, such as that employed in making toy balloons. Upon the latter is wound the usual rubber thread 5 under high tension, and the whole is covered with a protective envelop 6, preferably of plastic material such as balata.

The mold which I have devised for forming the layer of molded elastic composition is one of the important features of my invention, and is particularly adapted for molding vulcanizable rubber compound although it is adapted for molding other compounds in which vulcanization is not necessary. This mold is shown in Figs. 3 and 4. It consists of upper and lower portions 7 and 8 within which are symmetrically located cavities which are adapted to form the central layer or body in spherical form for a portion thereof, each side of a central zone. The halves 7 and 8 of the mold are each provided with tapering pins 9 and 10, which are adapted to come accurately in contact with the metallic ball when in position for molding, as illustrated in Fig. 3. Four other similar pins are provided in the two halves of the mold cavities in the parts 7 and 8, as indicated by 11 and 12. These, preferably, do not extend inward sufficiently to contact with the ball 1, and being somewhat shorter, form similarly shaped but shallower pockets. The central equatorial zone of the ball is formed by a ring consisting of two parts 13 and 14 which fit in corresponding grooves or recesses in the mold sections 7 and 8. The ring sections are each provided with pins 15 and 16 which are similar to 9 and 10 and are adapted to contact with the surface of the metallic core when in position. The pins 9, 10, 15 and 16 therefore constitute six supporting or centering points for fixing the position of the metallic core accurately within the mold. Contrary to usual opinion, the pins do not, by reason of their convergence, prevent the molded layer from being easily removed from the mold and I have found that the composition is easily freed from the mold after vulcanization or molding. This is due to the fact that the rubber when vulcanized possesses substantially the same elastic resilient characteristics of the ordinary soft rubber. In the present instance to remove the rubber sphere from the mold sections the upper section 7 is raised, thereby simultaneously freeing the vulcanized sphere from both the mold section and attached pins. The lower section 8 may be removed in a similar manner. The sections 13 and 14 may then be removed by similarly withdraw-

ing them in a radial direction from the rubber sphere, the sphere yielding and stretching to permit the radially disposed pins to be freed from their engagement with the converging openings in the sphere. The mold sections may be provided with the usual overflow recesses 17, if necessary.

When rubber composition is to be vulcanized the mold sections are filled with raw rubber composition and the ball placed in position on the centering pins. The mold is then placed between the steam-heated platens of an hydraulic press and the rubber cured or vulcanized in the usual way. If the composition is one which is merely required to set, the material may be poured into the mold through a suitable opening or openings.

What I claim and desire to protect by Letters Patent is:

1. A mold for bodies of elastic material comprising mold sections having symmetrical cavities therein which register with each other, and tapering pins extending radially from the surfaces of said cavities toward a common center.

2. A mold for spherical bodies of elastic material comprising mold sections having semi-spherical cavities therein, and tapering pins extending radially from the surfaces of said cavities toward the center.

3. A mold for spherical bodies of elastic material comprising mold sections having semi-spherical cavities therein, tapering pins extending radially from the surfaces of said cavities toward the center thereof, equatorial ring sections adapted to be seated in recesses in said mold sections, and pins extending from said ring sections toward said center.

4. A method of molding elastic bodies having converging openings, comprising placing moldable material in a mold having tapering radial pins converging toward a common center, and symmetrically located at substantially equal distances apart throughout the entire mold cavity, allowing said material to harden or set, and then withdrawing said material over said pins.

5. A method of making elastic bodies having converging openings, comprising locating a hard spherical ball accurately upon a series of radial pins symmetrically located at substantially equal distances throughout the entire mold cavity, surrounding said ball with moldable material, allowing said material to harden or set, and then removing the molded body by withdrawing the same over said pins.

6. A method of molding spherical bodies 60 of elastic material having converging openings therein, comprising locating a hard spherical ball accurately upon a series of radial tapering pins within a sectional mold and extending inward from six symmetrical 65 points, surrounding said ball with moldable material, allowing said material to harden or set, and then removing the molded body by withdrawing the same over said pins.

7. A mold for spherical bodies of elastic 70 material comprising mold sections having pins extending from the mold walls into the mold cavity symmetrically located at substantially equal distances throughout the entire cavity.

8. A mold for spherical bodies of elastic material comprising mold sections forming collectively a spherical cavity, and pins extending into said cavity from the wall of the sections and symmetrically located at substantially equal distances throughout the cavity and terminating at equal distances from the center of the cavity.

9. A mold for spherical bodies of elastic material comprising mold sections forming 85 collectively a spherical cavity, and sets of pins extending into said cavity from the walls of the sections, one set of said pins being symmetrically located and equally spaced and terminating at equal distances 90 from the center of the cavity, and another set of said pins being symmetrically located and equally spaced and terminating at equal distances from the center of the cavity but at a greater distance than the first set.

10. A method of molding elastic bodies having converging openings, which consists in placing moldable material in a sectional mold having radial pins converging from the respective mold sections toward a common center, allowing said material to set into a yieldable mass, and then withdrawing said material from the respective mold sections and their converging pins simultaneously.

11. A method of molding elastic bodies having converging openings, comprising placing moldable material in a sectional mold having a plurality of radial pins converging from the wall of each section toward a common center, allowing said material to set into a yieldable mass, and then withdrawing said material simultaneously over said converging pins and from the mold section to which they are secured.

Signed at Providence, R. I., this 4 day of January, 1917.

HENRY Z. COBB.
